BUCKAU, GERMANY

MACHINE FOR WINDING OR COVERING CABLES OR THE LIKE WITH TAPE OR STRIP
MATERIAL

Application filed March 5, 1927, Serial No. 173,152, and in Germany March 6, 1926.

This invention relates to machines for winding or covering cables or the like with tape or strip material, such machines being hereinafter referred to as multiple tape 5 winders.

In multiple tape winders as previously constructed, the spools are mounted in an adjustable manner by means of specially constructed holders on the rods of the winding 10 frame, which rods extend parallel to the axis of the cable or the like on which the tape or strip material is to be wound. Owing to the arrangement of the spools on the rods of the winding frame, multiple tape winders, 15 as previously constructed are necessarily of considerable length and this fact is open to certain objections. Furthermore, and in order to adjust the winding angle and the lapping of the tapes relatively to one another (i. e., positive or negative overlap or 20 butt joint) the spools, together with their holders, have to be moved on the rods of the spinning frame and this adjusting operation is not only difficult but occupies a 25 considerable period of time.

According to the present invention the aforesaid disadvantages are avoided by mounting the spools on the spinning frame in such a manner that their central axes are 30 situated in planes at right angles to the axis of the cable or the like on which the tape or strip material is being wound. Furthermore, the spools, or the spindles on which they are rotatably mounted, are also prefer- 35 ably so arranged that the mid-plane of each spool (which mid-plane is situated at right angles to the axis of the spool) is tangential or approximately tangential to the cable or the like at the winding-on point of the tape.

40 It is particularly suitable to construct the winding machine in such a way, that all the spools can be adjusted or set simultaneously, and to this end, the spool holders for all the spools of a series are connected to a common 45 or combined setting device. The setting of the spools may be effected, for example, by means of a disc which is jointed or pivotally connected to all the spool holders on the winding head, the said disc being mounted on 50 the winding head in such a manner that it is

capable of being rotated or angularly displaced around or relatively to the axis of the cable on which the tape or strip material is being wound and thereafter locked in its adjusted position.

55 In order that the said invention may be clearly understood and readily carried into effect the same will now be described more fully with reference to the accompanying drawings which show two embodiments of 60 the subject matter of the invention by way of example.

Figure 1 is a partly diagrammatic cross-sectional view of part of a multiple tape winder constructed according to the first 65 embodiment of the present invention, the section being taken through the axis of the cable on which the tape or strip material is being wound and showing the spools in elevation looking in the direction of the cable. 70

Figure 2 is a diagrammatic perspective view of two of the spools looking in a direction transversely of the cable axis.

Figure 3 is a plan showing the winding-on 75 points of a cable on which tapes have been wound by a machine constructed according to the present invention, and

Figure 4 is a diagrammatic elevation showing in their individual positions relatively to 80 the cable the guiding devices inserted between the spools and the cable but, for the sake of clearness, these devices, which are actually situated around the cable are shown in the same plane.

85 The second embodiment will be described with reference to the following drawings, in which

Figure 5 is a cross-section taken through the cable axis showing, in elevation, the arrangement of the spools looking in the direction of the cable axis, and

Figure 6 is a part sectional side elevation of Figure 5 two of the spools only being shown for the sake of greater clearness.

90 Referring to the drawings showing the first embodiment 1 is the cable on which the tape or strip material is to be wound, and 2, 3, 4, 5, 6 and 7 are six spools which are mounted on the winding frame and arranged, for 100

instance at an angle of 60° relatively to one another, in such a manner that their axes $2a$, $3a$, $4a$, $5a$, $6a$ and $7a$ are situated, for example, at approximately equal distances from the axis $1a$ of the cable 1 and at right angles to the cable axis; the mid-planes $2b$, $3b$, $4b$, $5b$, $6b$ and $7b$ of the said spools, which mid-planes are situated at right angles to the axes $2a$, $3a$, $4a$, $5a$, $6a$ and $7a$, being tangential or approximately tangential to the cable 1 at the winding-on points of the tapes. Each of the said spools is rotatably mounted on the spindle 8 of a holder 9, which latter is adjustably mounted in any suitable manner on a rod 22 of the winding frame which rod extends parallel to the cable axis. The tapes, at the points where they leave the spools, are each led over a guiding device which guiding device can also be utilized as a braking device. Each said combined device may be constituted by a pair of pins numbered 10 to 15 and 16 to 21 respectively, each pair of pins being preferably arranged parallel to one another and to the axis of its corresponding spool. Instead of using two separate pins, a single pin is formed into a staple by being bent into U-shape and between the arms of each U-shaped staple the tape from the respective spool passes in the manner shown at Figures 2 and 4. Each of the aforesaid combined guiding and braking devices is mounted on its respective holder in such a manner that its distance relatively to the cable 1 can be adjusted, this adjustment being preferably effected in an approximately radial direction relatively to the cable axis (see more particularly Figure 4). Furthermore, each of the combined guiding and braking devices is rotatable about the central axis of the pin from which the tape runs directly to the cable (see for instance 14 and 15 and in particular Figure 2). The braking of the tape at the point where it leaves the guiding pin can be effected by rotating the combined braking and guiding device in the direction of the arrow y (Figure 2). Between the point where each tape leaves its guiding or braking pin and the point where it is wound on to the cable the tape is twisted 90° in the usual manner. Owing to the twisting of the tape the formation of folds or kinks at the point where each tape leaves its guiding or braking pin is avoided, such kinks being liable to break the tape. Furthermore, owing to the approximately radial movement of the combined guiding and braking devices it is possible to cause the successive layers of tape to be wound on the cable in such a manner that the edges of each spiral lap are shifted to any given extent relatively to one another, for example, for the purpose of covering the joints of a preceding layer or lap by those of the next layer or lap, this adjustment being effected without varying the position of the tape spools. Furthermore, any necessary

setting of the relatively small combined guiding and braking devices can be effected in a very simple and accurate manner.

Before commencing the winding operation the spools are first set by means of the holders 9 rotatably mounted on the rods 22 in accordance with a scale 23 so as to suit the diameter of the cable portion which is to be wound or which has already been partly wound that is to say, preferably in such a manner that the mid-planes of the spools, which mid-planes are at right angles to the axes of the spools, are substantially tangential to the cable at the point where the tape runs on to the cable. The aforesaid combined guiding and braking devices are then set in such a manner that they are situated on say a spiral rising in the opposite direction to the arrow z (i. e. the direction of rotation of the winding frame—see Figure 1), that is to say at different distances from the cable axis (compare the relative position of the devices shown in Figure 4). If, moreover, the combined guiding and braking devices are also situated in a plane at right angles to the cable axis (see Figure 4) it follows that the tapes will be consecutively wound on the cable at equal distances apart. A modification of the relative position of the tapes which are being wound on the cable can be effected by a corresponding movement either of the holders 9 on the rod 22, that is to say axially of the cable, or by altering the distance of the combined guiding and braking devices from the axis of the cable. This alteration can be effected, for example, by moving the said devices on the holders 9 approximately radially of the cable.

The reduction in length of the winding-on portion produces other important advantages. If, for example, the cable is wound by different winders in a clockwise as well as an anticlockwise direction (left and right hand winding) the twisting of the cable, which of course increases with the length of the cable portion which is used for each winding, is reduced to a minimum or entirely avoided in cases where right and left hand winding closely follow one another. Moreover the cable can be held by guides at considerably shorter distances apart than hitherto. Consequently, any deviation of the cable from a straight line which might cause breaking of the tape is avoided.

In the embodiment represented in Figures 5 and 6 likewise six tape spools 25, 26, 27, 28, 29 and 30 are arranged around the cable 24 or the like on which the tape or strip material is to be wound and at an angle of 60° relatively to one another. Each spool is rotatably mounted on a spindle 31 of a holder consisting of two telescoping parts 32 and 32' adapted to be secured together by a set screw 45. Each holder part 32 is provided with an arm 33 mounted in an oscillating manner on a pin 34, secured to the winding head 130

35. On the winding head 35 a disc 36 is also provided which is rotatable or angularly displaceable about the axis of the cable 24. The disc 36 is provided with six radial slots 37, which are engaged by six pins 38 provided on the arms 33 of the holder parts 32. The rotation or angular adjustment of the disc 36 is effected by means of a lever 39 connected thereto, and lever 39 can be locked relatively to the winding head 35 by means of a set screw or clamping device 40. On each holder 32' is mounted a rod 41 (Figure 6) which is adjustable in a direction approximately parallel to the cable 24 and which is adapted to carry a guiding and braking device 42.

10 The operation of the device will be clear from the aforesaid description and consequently does not need further explanation.

15 It is to be understood that it is immaterial so far as the present invention is concerned in what manner the combined adjustment or setting of all the tape spools is effected. The rotation or displacement of the disc 36, as well as the transmission of its movement of 20 rotation or angular displacement to the tape spools can, if desired be effected in some other manner than that previously described.

25 What we claim is:

1. A machine for winding cables or the like 30 with strip material, comprising a winding frame, axles on said winding frame at right angles to the axis of the cable, and spools rotatably mounted on said axles, the mid-planes of said spools, which are perpendicular to 35 the axes of the spools, being substantially tangent to the cable at the winding-on points.

2. A machine for winding cables or the like 40 with strip material, comprising a winding frame, axles on said winding frame at right angles to the axis of the cable, spools rotatably mounted on said axles, the mid-planes of said spools, which are perpendicular to the axes of the spools, being substantially 45 tangent to the cable at the winding-on points, and guiding and braking devices consisting of two arms arranged parallel to one another and to the axis of the corresponding spool over which arms the tape is guided.

50 3. A machine for winding cables or the like 55 with strip material in accordance with claim 2 in which said guiding and braking devices are angularly adjustable for varying the braking effect.

4. A machine for winding cables or the like 60 with strip material, comprising a winding frame, holders mounted upon said frame and adapted to be adjusted longitudinally with respect to the cable and angularly about an axis parallel to the cable, axles on said 65 holders at right angles to the cable, spools mounted upon said axles and guiding and braking devices mounted on said holders consisting of two arms arranged parallel to one

another and to the axis of the corresponding spool over which arms the tape is guided.

5. A machine for winding cables or the like 70 with strip material in accordance with claim 4 in combination with a common control member for simultaneously adjusting said holders angularly.

6. A machine for winding cables or the like 75 with strip material in accordance with claim 4 in combination with a disc angularly displaceable around the axis of the cable, connections between said disc and said holders adapted to translate angular displacement of said disc into angular adjustment of said holders, and means for locking said disc in 80 adjusted position.

7. A machine for winding cables or the like 85 with strip material in accordance with claim 4 in which said guiding and braking devices are mounted upon rods adapted to be adjusted parallel to the cable, and means for locking said rods in adjusted position.

8. A machine for winding cables or the like 90 with strip material, comprising a winding frame, axles on said winding frame at right angles to the axis of the cable, said axles being adjustable about axes parallel to the axis of the cable, spools rotatably mounted on said axles, and guides for each spool 95 mounted to be adjustable as a unit with the axles upon which their respective spools are mounted.

9. A machine for winding cables or the like 100 with strip material, comprising a winding frame, axles on said frame at right angles to the axis of the cable, said axles being adjustable about axes parallel to the cable, a common adjusting device connected with all said axles and adapted to adjust them simultaneously about said axes parallel to the cable, and spools rotatably mounted upon said axles.

105 The foregoing specification signed at Berlin, Germany, this 16th day of February, 1927.
